UNITED STATES PATENT OFFICE.

REUBEN L. ALLEN, OF PROVIDENCE, RHODE ISLAND.

WATCH-CHARM.

SPECIFICATION forming part of Letters Patent No. 298,540, dated May 13, 1884.

Application filed March 17, 1884. (No model.)

To all whom it may concern:

Be it known that I, REUBEN L. ALLEN, of Providence, in the State of Rhode Island, have invented an Improvement in Magnifying-Glass Holders and Watch-Charms, of which the following is a specification.

My invention consists in the improved construction of the case, whereby the pivoted setting-rim of the holder or charm is tightly set 10 cured in its closed position and the entrance of dust and dirt prevented.

Figure 1 is an edge view of my improved magnifying-glass holder adapted to be worn as a watch-charm. Fig. 2 is a side view of the 15 same opened. Fig. 3 is a vertical section showing the holder closed. Fig. 4 is a vertical section of the same when partly opened. Fig. 5 is an edge view, and Figs. 6 and 7 vertical sections, showing a locking device which 20 is operated by a sidewise movement of the fastening-ring.

In the accompanying drawings, A is the setting-rim adapted for holding the magnifying-lens or other desirable object for a charm, and 25 pivoted between the opposite plates, B B, of the case at the point b. The triangular guard C, made to fit the periphery of the setting-rim A, is provided with a ring, d, by means of which the whole may be suspended from a 30 chain, and the wire of the eye d will furnish a convenient thumb-piece for operating the guard C in opening and closing the holder or charm. When the setting-rim A is turned to

one side, the guard C will be also turned on its pivot e, as shown in Fig. 4, and the holder 35 fully opened is shown in Fig. 2.

In order to provide a lock for the setting-rim A when in its closed position within the case, I form a hollow, f, at the side of the setting-rim opposite to its pivot b, as shown in 40 Figs. 6 and 7, and pivot the guard C and ring d separately from each other upon the common pivot e. The opposite sides of the pivot-eye g of the ring d are cut away, as shown, in order to allow the holder or charm to be opened 45 when the ring has first been turned to one side, as shown in Fig. 7; but when held in a vertical position, as shown in Fig. 6, the setting-rim A will be firmly locked, by reason of the close fitting of the hollow f with the cylindrical lower portion of the pivot-eye g.

I claim as my invention—

1. The combination of the pivoted setting-rim A, case B B, and the pivoted guard C, adapted to fit the periphery of the setting-rim 55 A, substantially as described.

2. The combination of the pivoted setting-rim A, provided with the hollow f, case B B, pivoted guard C, adapted to fit the periphery of the setting-rim A, and the ring d, provided 60 with the pivot-eye g, cut away at its side, substantially as and for the purpose specified.

REUBEN L. ALLEN.
